DISHWASHING MACHINE

George R. Porter, West Hartford, Conn., assignor
to Colt's Manufacturing Company, a corpora-
tion of Connecticut

Application March 24, 1945, Serial No. 584,578

4 Claims. (CL. 134—48)

1

This invention relates to improvements in a dishwashing machine and more particularly to the provision of a pre-rinse device within the cabinet of a dishwashing machine in which conventional washing and rinsing compartments are provided.

It is an object of the present invention to reduce the bacteria count in the washing and rinse water used in a dishwashing machine having washing and rinsing compartments by including a pre-rinse device within the cabinet of the dishwashing machine, said pre-rinse device maintaining said washing and rinse water cleaner for a considerably longer time than in conventional machines not provided with a pre-rinse device.

It is another object of the invention to increase the washing efficiency of a conventional dishwashing machine by providing therein a pre-rinse device in that it has been found that wet dishes may be thoroughly washed in less time and with less washing solution than dishes which are introduced into the washing compartment in substantially dry condition.

It is a further object of the invention to incorporate within the pre-rinse device a foraminous scrap tray which will collect all scraps and other soil removed by the pre-rinse device from the dishes to be washed prior to the passage of said dishes into the washing compartment.

It is still another object of the invention to utilize unheated water at normal pressure within said pre-rinse device, said water being drained from the soiled dishes into a tank connected directly with the drain of the dishwashing machine and separate from the tanks into which the washing and rinse waters flow.

Other objects of the invention as well as the details of the invention and details of the foregoing objects are set forth in the following specification and illustrated in the accompanying drawings. Said drawings are to be considered only as illustrative of the principles of the invention and are not intended to restrict the invention in any way since it is to be understood that changes, variations and modifications can be resorted to which come within the scope of the claims appended hereto.

In the drawings, Fig. 1 is a side elevation of a dishwashing machine embodying the invention and comprising a cabinet having thereon a pre-rinse device, a washing compartment, a hot rinse compartment, and a final rinse device.

Fig. 2 is an elevation, partly broken away to better illustrate details of the invention, said end

2

being that in which the entrance of the dishwashing machine is located.

Fig. 3 is a top plan view of the dishwashing machine illustrated in Fig. 1.

Fig. 4 is a fragmentary sectional elevation taken on the line 4—4 of Fig. 3 and illustrating the effect of the spray arrangements of the pre-rinse device.

Fig. 5 is a fragmentary sectional plan view taken on the line 5—5 of Fig. 1.

Fig. 6 is a fragmentary sectional plan view taken on the line 6—6 of Fig. 1.

Fig. 7 is a fragmentary top plan view of a portion of the top spray pipe or manifold of the pre-rinse device, said view illustrating the oblique arrangement of the sheet-like sprays.

In describing the foregoing objects of the invention and in the following specification and claims, the term "normal pressure" used to de-

scribe the water utilized in the pre-rinse device is intended to denote so-called city pressure or the pressure at which water is supplied to the kitchen in which the dishwashing machine is used irrespective of the pressure developed by the pump or pumps of the dishwashing machine. Similarly, the term "unheated" as used to describe the aforementioned water is intended to denote water at the temperature at which it is obtained from the so-called cold water supply of the kitchen in which the washing machine is used and irrespective of heated water which may be furnished by a hot water heater attached to the dishwashing machine or otherwise provided in the kitchen for purposes of furnishing hot water for general use or for use in the washing and hot rinse compartments or final rinse device of a dishwashing machine.

Further, the term pre-rinse device as used within this specification and the claims appended thereto is preferably but not restrictively intended to denote a spray arrangement located adjacent the entrance of the cabinet of a dishwashing machine, said arrangement being so positioned that the water sprayed therefrom contacts soiled dishes prior to their entering the washing compartment. Said pre-rinse device is to be distinguished from such terms as rinse device or compartment, hot rinse device or compartment and final rinse device. All of said rinse devices and/or compartments except the pre-rinse device are located rearward of the washing compartment relative to the direction of the movement of dishes through the dishwashing machine.

The matter of thoroughly washing dishes with

a minimum quantity of hot water is of prime importance since heating water to the necessary temperature for properly washing dishes in a dishwashing machine is expensive, particularly when it is considered that extensive quantities of hot water are usually required to wash dishes in conventional dishwashing machines of the types now available. Predicated upon the fact that a wet dish may be washed more quickly and with a smaller quantity of water or washing solution than a dry or substantially dry soiled dish, the present invention was conceived for purposes of reducing to a minimum the quantity of hot washing and rinse water required in conventional dishwashing machines.

The inclusion of a pre-rinse device within a conventional dishwashing machine imposes no added burden on the heating facilities for the water used within the washing and rinse, hot rinse, or final rinse compartments or devices. Similarly, the capacity of the conventional pump or pumps of the dishwashing machine need not be increased since the same are not needed to supplement the normal pressure at which the water is supplied for use in the pre-rinse device from the so-called cold water supply of the kitchen in which the machine is used.

Said pre-rinse device removes the bulk of the particles of scrap and other soil from the dishes to be washed, said scrap and soil being either collected in a scrap receptacle or sluiced to the main drain for the dishwashing machine without polluting or chilling the water within the tanks of the washing and rinse compartments of said machine. Hence, the soiled dishes are fed to the washing compartment in a cleaner condition than normally and also while wet, whereby the hot water in the washing compartment will completely wash the remaining soil from the wet dishes in shorter time than it would from dry dishes and with much less consumption of hot water than is now required in conventional dishwashing machines. These beneficial results are attained, as explained above, at no increase in the conventional costs of operating a dishwashing machine other than the cost of supplying a small amount of additional unheated water at normal or so-called city pressure, said cost being insignificant.

Explaining the preferred embodiment of the invention and referring to the details illustrated in the drawings, particularly Figs. 1 through 3 thereof, the dishwashing machine 10 comprises a substantially unitary cabinet 12 including a washing compartment 14, a rinse or hot rinse compartment 16 and a final rinse device 18. Water is supplied to sets of conventional main spray devices or manifolds 20, 22 within said compartments from a plurality of pumps 26, 28 which pump water from tanks 30 and 32 within said machine.

Water overflows from tank 32 into tank 30 and then into the top of standpipe 34, from which it flows into the main drain 36 of the machine.

Final rinse device 18 is supplied from any suitable source with heated water, said supply being controlled by a valve 38 actuated by a movable arm 40.

Extending through the cabinet 12 for substantially the full length thereof is a conveyor 42 comprising a pair of spaced sprocket chains which are driven by another sprocket chain 44 actuated by a gear reduction mechanism 46. The latter is driven by motor 48 which also drives pumps 26 and 28.

The conveyor 42 is designed to support and move racks or trays 50, hereinafter generally referred to as trays, through the various compartments and past the several spray devices of the dishwashing machine. Each tray 50 is sufficiently open at the bottom to permit dishes therein to be acted upon by sprays directed upwardly from positions below the path of tray movement. As the trays 50 pass through the hot rinse compartment 16 and approach the final rinse device 18, said trays engage arm 40 of valve 38 and move the same in a direction to open said valve and cause heated water to be sprayed from the manifolds 24 of said device. When said trays have passed said arm, the valve is automatically closed in order that water for the final rinse device may be conserved and only used at such times as trays are moving therewith. Further, said water from the final rinse drains into tank 32 of the hot rinse compartment and then overflows into the washing solution of tank 30. Only intermittent use of the final rinse water is thus desired to reduce to a minimum the dilution of said solution.

The present invention comprises lengthening the cabinet of a conventional dishwashing machine at the entrance end thereof in order to provide a compartment 52 within which to mount a pre-rinse device and scrap collector for purposes of attaining the aforementioned objects and benefits.

The pre-rinse device has an inlet pipe 54 which is connectible with the cold water supply for the kitchen in which the machine is used. Said inlet pipe leads to a valve 56 which is similar to valve 38 and includes an arm 58 corresponding to arm 40. Said valve is connected by suitable piping to a vertical pipe 60 which is connected to and supports at its upper end a top spray device or manifold 62 disposed horizontally and provided on its underside with a series of spaced slots 64 arranged obliquely to the longitudinal axis of said manifold but parallelly to each other.

The lower end of vertical pipe 60 supports and is connected to a bottom or lower spray device or manifold 66 provided in its upper surface with a series of spaced slots 68 arranged in end to end relationship along a substantially straight line parallel to the axis of said manifold as best shown in Fig. 5.

When a tray 50 containing properly stacked soiled dishes is introduced to the conveyor through the entrance 70 of the dishwashing machine, said tray is moved by conveyor 42 into contact with arm 58 which opens valve 56 to permit water to be sprayed at normal pressure from top manifold 62 and bottom manifold 66 of the pre-rinse device for purposes of sluicing scrap and soil from said soiled dishes prior to said dishes reaching washing compartment 14. The scraps and soil removed from said dishes pass through the bottom of the tray 50 and into a scrap collecting basket 72 preferably formed of mesh material to catch and retain such scrap as would cause clogging of the drain. In order that said basket 72 need not be unduly large, a funnel-like deflector 74 comprising four connected baffles sloping downward toward the center is disposed beneath said pre-rinse device and the central opening in the bottom of device 14 is of such dimensions that the perimeter thereof extends a suitable distance inward past the sides of basket 72 as is clearly shown in Figs. 1 and 4.

Water sprayed from said pre-rinse device

passes through the basket 72 and into a receptacle 76 which is separated and preferably adequately spaced from tank 30 to prevent any appreciable heat exchange therebetween. The receptacle 76 is provided with a bottom comprising sloping connected walls 78 which are connected at their lower edges to a small apertured bottom member 80 communicating with drain 36.

Access to the receptacle 76 may be obtained through opening 82 or entrance 70. Opening 82 is normally closed by a slidable door 84 removably maintained in water-tight engagement with the side wall of tank 76 containing opening 82. Opening 82 is of sufficient size to readily permit passage of basket 72. Said basket is retained in operative position by a pair of angular members 86 and 88 clearly shown in Figs. 2 and 4. When basket 72 has been removed through opening 82, all parts of the interior of the tank 76 are readily accessible for cleansing at the conclusion of using the dishwashing machine each day or at such other times as may be necessary.

Access to pre-rinse compartment 52 is obtained either through entrance 70 or through opening 90 provided in the side of the cabinet 12 adjacent valve arm 58. Opening 90 is normally closed by a slidable door 92 removably maintained in water-tight engagement against the side of the cabinet containing said opening 90.

A curtain 94, preferably, is at least partially suspended over entrance 70 and, if desired, a second curtain 96 may be suspended inward of the compartment 52 from curtain 94. These curtains prevent the escape of pre-rinse water through the entrance opening 70.

In accordance with the invention, there are upper and lower partitions which provide separate pre-rinse and washing compartments in the cabinet 10, the pre-rinse devices being in the pre-rinse compartment and the sets of main washing and rinsing devices being in the washing compartment. The upper partition is shown at 97 in Figs. 1, 2 and 4, this partition being chiefly above the path of dish movement and comprising fixed metallic walls and also comprising a curtain 98. The curtain 98 is preferably formed of durable cloth material and is readily moved out of its normal position by a tray 50 or by dishes carried thereby. The lower partition is the rear wall 99 of the receptacle 76 which receives the pre-rinse water. These partitions prevent any intermingling between the pre-rinse water and the washing liquids, such intermingling being prevented both above and below the path of dish movement.

The pre-rinse spray devices 62 and 64 are substantially spaced longitudinally from the first of the said sets of main spray devices, such as 20, 20. This wide spacing serves, in cooperation with the partitions, to prevent intermingling between the pre-rinse water and the washing liquids, and it has the further and very important advantage that it provides a substantial interval of time between the action of the pre-rinse devices and the action of the first main washing devices. This greater interval of time enables the pre-rinse water to soak into and soften any soil on the dishes. Preferably and, as shown, the sprays are so spaced longitudinally that the distance between the pre-rinse spray devices and the first set of main washing devices is considerably greater than the spacing between any two of the sets of main spray devices such as 20, 20 and 22, 22 and 18.

In order that the pre-rinse device will function most efficiently to remove scraps and soil from

surfaces exposed to the top as well as the bottom of trays 50, it will be observed that both an upper and a lower manifold 62 and 66 are provided in said device. It will be observed that the obliquely arranged slots 64 provide a series of parallel fan-shaped curtains or flat sprays of water 65 as illustrated in Figs. 4 and 7 while slots 68 furnish a single curtain of water 100 illustrated in Fig. 4, whereby the sprays of water coming from the slots 60 and 68 respectively provided in said manifolds will not unduly conflict with each other. Said single curtain of water 100 thus serves, in effect, to bisect the plurality of fan-shaped sprays of water 65 from slots 64 but, otherwise, said curtain of water 100 does not interfere with the free flowing of said sprays 65 coming from slots 64. The plurality of oblique sprays 65 afford such an extensive spray area that, when supplemented by curtain of water 100, it affords complete wetting and efficient pre-rinsing of all soiled dishes within trays 50.

Manifolds 62 and 66 have been illustrated as being respectively provided with slots 64 and 68, but it is to be understood that, if desired, spray nozzles or ports may be mounted within said manifolds in lieu of forming said slots therein.

In the foregoing specification and the claims appended hereto, it is to be understood that the term "dishes" is used in the generic or general sense to refer to all types of dishes made from ceramic, plastic or metallic materials or otherwise, glasses, goblets, silverware, and all other receptacles, utensils and implements used in the preparation and cooking of food and beverages and in serving and eating or drinking the same.

While the invention has been illustrated and described in its preferred embodiment and has included certain details, it should be understood that the invention is not to be limited to the precise details herein illustrated and described since the same may be carried out in other ways, falling within the scope of the invention as claimed.

What I claim is:

1. In a dishwashing machine, the combination of a cabinet having a front entrance opening and a rear discharge opening; means within the cabinet for guiding dishes therethrough along a fixed path from the entrance opening to the discharge opening, upper and lower partitions extending across the cabinet near the front end and providing separate pre-rinse and washing compartments, a plurality of sets of main washing and rinsing spray devices within the washing compartment of the cabinet and longitudinally spaced from each other along the path of dish movement, means for supplying heated washing and rinsing liquids under pressure to the said main spray devices to enable them to forcibly deliver sprays of liquid against the dishes to effect washing and final rinsing as the dishes are moved along the said path, pre-rinse spray devices within the pre-rinse compartment of the cabinet and located respectively above and below the path of dish movement, the said pre-rinse spray devices being longitudinally spaced a substantial distance from the first of the said sets of main spray devices, means independent of the aforesaid means for supplying liquids to the main spray devices for supplying unheated water at normal pressure to the said pre-rinse spray devices to enable them to deliver sprays of water downwardly and upwardly against the dishes to pre-rinse them and wet them, the last said spray devices being separated from the first of the sets of main spray devices by the said partitions.

which serve to prevent any substantial intermingling between the pre-rinse water and the liquids delivered by the main spray devices, and means located within the pre-rinse compartment and below the path of dish movement for receiving the water delivered by the pre-rinse spray devices.

2. In a dishwashing machine, the combination of a cabinet having a front entrance opening and a rear discharge opening, means within the cabinet for guiding and moving dishes continuously therethrough along a fixed path from the entrance opening to the discharge opening, a plurality of sets of main washing and rinsing spray devices within the cabinet longitudinally spaced from each other along the path of dish movement with the first of the said sets spaced a substantial distance from the front end of the cabinet, means for supplying heated washing and rinsing liquids under pressure to the said main spray devices to enable them to forcibly deliver sprays of liquid against the dishes to effect washing and final rinsing as the dishes are moved along the said path, pre-rinse spray devices within the cabinet adjacent the entrance end thereof and located respectively above and below the path of dish movement, the said pre-rinse spray devices being longitudinally spaced from the first of the said sets of main spray devices by a substantial distance considerably greater than the longitudinal distance between any two of the sets of main spray devices, means for supplying unheated water at normal pressure to the said pre-rinse spray devices to enable them to deliver sprays of water downwardly and upwardly against the dishes to pre-rinse them and wet them, the last said means being independent of the aforesaid means for supplying liquids to the main spray devices, means located below the path of dish movement for receiving the water delivered by the pre-rinse spray devices and serving to prevent any intermingling below the said path between the said pre-rinse water and the liquids supplied to and delivered by the main washing and rinsing sprays, and a partition extending across the cabinet above the path of dish movement and between the pre-rinse spray devices and the first set of main spray devices, the said partition serving to prevent any substantial intermingling above the said path between the said pre-rinse water and the liquids delivered by the main spray devices.

3. In a dishwashing machine, the combination of a cabinet having a front entrance opening and a rear discharge opening, means within the cabinet for guiding dishes therethrough along a fixed path from the entrance opening to the discharge opening, a plurality of sets of main washing and rinsing spray devices within the cabinet longitudinally spaced from each other along the path of dish movement with the first of the said sets spaced a substantial distance from the front end of the cabinet, means for supplying heated washing and rinsing liquids under pressure to the said main spray devices to enable them to forcibly deliver sprays of liquid against the dishes to effect washing and final rinsing as the dishes are moved along the said path, pre-rinse spray devices within the cabinet adjacent the entrance end thereof and located respectively above and below the path of dish movement, the said pre-rinse spray devices being longitudinally spaced a substantial distance from the first of the said sets of main spray devices, means for

supplying unheated water at normal pressure to the said pre-rinse spray devices to enable them to deliver sprays of water downwardly and upwardly against the dishes to pre-rinse them and wet them, the last said means being independent of the aforesaid means for supplying liquids to the main spray devices, a partition extending across the cabinet above the path of dish movement and between the pre-rinse spray devices and the first set of main spray devices, the said partition serving to prevent any substantial intermingling above the said path between the said pre-rinse water and the liquids delivered by the main spray devices, means located below the path of dish movement for receiving the water delivered by the pre-rinse spray devices and serving to prevent any intermingling below the said path between the said pre-rinse water and the liquids supplied to and delivered by the main washing and rinsing sprays, and a removable scrap basket below the pre-rinse spray devices and below the path of dish movement and above the said means for receiving the said pre-rinse water.

4. In a dishwashing machine, the combination of a cabinet having a front entrance opening and a rear discharge opening, two parallel transversely spaced endless chains within the cabinet for moving therethrough along a fixed path from the entrance opening to the discharge opening a succession of dish carrying trays which are sufficiently open at the bottom to permit upwardly directed sprays to engage the dishes, a plurality of sets of main washing and rinsing spray devices within the cabinet longitudinally spaced from each other along the path of tray movement with the front of the said sets spaced a substantial distance from the front end of the cabinet, means for supplying heated washing and rinsing liquids under pressure to the said main spray devices to enable them to forcibly deliver sprays of liquid against the dishes carried by the said trays to effect washing and rinsing as the dishes are moved by the trays along the said path, pre-rinse spray devices within the cabinet adjacent the entrance end thereof and located respectively above and below the path of tray movement, the said pre-rinse spray devices being longitudinally spaced a substantial distance from the first of the said sets of main spray devices, piping for supplying unheated water at normal pressure to the said pre-rinse spray devices to enable them to deliver sprays of water downwardly and upwardly against the dishes to pre-rinse them and wet them, the said piping being independent of the aforesaid means for supplying liquids to the main spray devices, a normally closed valve connected with the said piping, actuating means for the valve normally projecting into the path of movement of the trays and operable when engaged by a tray to open the valve when a tray is between the pre-rinse spray devices, means located below the path of tray movement for receiving the water delivered by the pre-rinse spray devices and serving to prevent any intermingling below the said path between the said pre-rinse water and the liquids supplied to and delivered by the main washing and rinsing sprays, and a partition extending across the cabinet above the path of tray movement and between the pre-rinse spray devices and the first set of main spray devices, the said partition serving to prevent any substantial intermingling above the said path between the said pre-rinse

water and the liquids delivered by the main spray devices.
